UNITED STATES PATENT OFFICE

102,573

DESIGN FOR A COMBINATION CLOCK AND CALENDAR

Joseph C. Morris, Chicago, Ill.

Application November 11, 1936, Serial No. 65,842

Term of patent 7 years

To all whom it may concern:

Be it known that I, Joseph C. Morris, residing at Chicago, in the county of Cook and State of Illinois, have invented a new, original, and ornamental Design for a Combination Clock and Calendar, of which the following is a specification, reference being had to the accompanying drawing, forming part thereof.

In the drawing:

Fig. 1 is a front elevation of a combination clock and calendar, showing my new design.

Fig. 2 is a plan view of the same.

The numerals and printed matter shown in Fig. 1 are merely representative.

I claim:

The ornamental design for a combination clock and calendar, as shown and described.

JOSEPH C. MORRIS.
